HAIR WAVING DEVICE

Filed Nov. 12, 1930

UNITED STATES PATENT OFFICE

SOTER B. TUSIS, OF NEW YORK, N. Y.

HAIR WAVING DEVICE

Application filed November 12, 1930. Serial No. 495,221.

This invention relates to hair waving, and the primary object thereof is to provide a novel and improved device for giving a wave to the hair which will persist with a perfect natural wave effect as attempted to be obtained by the so-called finger wave or by the so-called Marcel wave.

An object of the invention is to provide a device of the kind just indicated, wherein 10 an exceedingly compact and inexpensive device is provided yet one so efficient that the hair may be given different wave effects at different times, or different wave effects at different portions at one time, in every case 15 with great convenience and rapidity.

Another object is to provide a device having some or all of the advantages just indicated, wherein the hair, even though given a permanent wave by the application of heat, will be 20 protected against breakage or damage to the individual hair filaments due to stretching any one or more thereof beyond the elastic limit.

A feature of the invention is the simple 25 construction of a hair waving device of improved action, and the simple manner in which such device may be connected to the hair and to the scalp, without discomfort to the latter from heat when heat is used, yet 30 with the device securely in place on the group or stand of hair filaments being waved, and at the same time in a readily attachable and detachable manner.

Other objects and advantages of the invention will be hereinafter specifically 35 pointed out, or will become apparent, as the specification proceeds.

With the above indicated objects in view, the invention resides in certain novel constructions and combinations and arrangement of parts, clearly described in the following specification and fully illustrated in the accompanying drawings, which latter shows an embodiment of the invention as at present 45 preferred.

In said drawings:

Fig. 1 is an elevational view, showing a strand of hair being wound upon said embodiment, the scalp being indicated in dot 50 and dash lines;

Fig. 2 is a perspective view of one of the elements of said embodiment;

Fig. 3 is a similar view of another of said elements;

Fig. 4 is a perspective view on a very 55 greatly enlarged scale, showing still a third element, and also indicating, in one case in dot and dash lines, in another case in broken lines and in another case in dotted lines various possible ways of winding a hair strand 60 relative to said element;

Fig. 5 is fragmentary radial sectional view, taken on the line 5—5 of Fig. 3, and showing the elements of Figs. 2 and 3 in section and certain parts of Figs. 1 and 2 in side elevation,—this Fig. 5 being a sectional view illustrating the elements when assembled as shown in Fig. 1; and

Fig. 6 illustrates at the left thereof the type 70 of wave which may finally be obtained in that part of the hair strand wound as shown in dot and dash lines in Fig. 4 and to the right thereof the tendril effect which may be imparted to a terminal subdivision of said hair strand when wound according to the 75 broken and dotted lines of Fig. 4.

Similar reference characters refer to similar parts throughout the several views of the drawings.

Referring to the drawings now more in 80 detail, the reference character 6 indicates in Fig. 1 the new device, as the same is here illustratively embodied for illustrating one of the many possible ways of carrying out the invention, in its entirety. In said Fig. 1 85 the scalp of the person whose hair is being waved is indicated at 7, and a strand of hair now receiving windings incident to a waving operation is indicated at 8. As is common, the basal portions of the filaments forming this particular strand may be wrapped and tied by a suitable cord or string as indicated at 9.

As will be seen best from Figs. 1 and 4, the new device includes as important elements 95 thereof a pair of elongate and more or less parallel, and preferably resilient, or resiliently anchored, posts, rods, wires, tubes or the like, in the present case indicated at 10a as being integral subdivisions of a single 100

length of bent wire 10. These subdivisions are the terminal portions of such wire, or equivalent, in the present case, and, conveniently, they are joined by a generally round loop 10b of a greater diameter than the distance between the posts 10a (as the subdivisions 10a will hereinafter be called), this loop being arranged in a plane substantially perpendicular to the plane containing the two posts.

10 The elements 11 and 12 of Figs. 2 and 3 are desirably of the same size, are made conveniently as circular discs as shown, and have matching holes 11a and 12a at or near their centers, and also similar radial slots 11b and 12b running from said holes to the peripheries of the discs.

15 In order that the discs 11 and 12 may be coupled whereby one may be rotated fractionally of the other, to place the slots 11b and 12b in registry (to cause the two discs to be straddlingly advanced over the basal portion of the hair strand), or in the reverse direction to stagger said slots (as shown in Fig. 1, thus to make the two discs a disengageable sleeving device for said basal portion of the hair strand), the following parts are provided: Arcuate slots 12c are cut through the disc 12, and there are secured to 20 the upper surface of the disc 11 a pair of female glove-fastener elements 14. The familiar central tubular studs of these elements 14 are extended into the slots 12c. Finally, the mating male glove-fastener elements 15 are inverted as shown in Figs. 1 and 5, and their familiar central studs are thrust down by way of said slots 12c into the interiors of 25 the studs of the elements 14.

30 The manner of attaching the elements 14 to the disc 11 is, conveniently, by way of stitching as indicated in Fig. 2; since, preferably the disc 11 is made of a soft felt. When said disc is of felt, it will be comfortable against the scalp, and will transmit very little if any heat to the scalp during the application of heat to a hair strand thereabove being subjected to a permanent waving operation. The stitching just referred to would then be very convenient, and, moreover, there would be no metal or other heat conducting or possibly uncomfortable part on the side of the disc facing the scalp.

35 The other disc 12 may, like the disc 11, be of any desired material, but at present this disc 12 is preferred to be made of a harder and stiffer material than felt, as metal, composition, leather, fiber or the like.

40 Before these discs are coupled as above explained, the bent wire member 10 is assembled as shown in Fig. 1, the posts 10a being thrust upwardly through apertures 12d, and the loop 10b being either squeezed down into the relatively soft felt material 45 of the lower disc 11 (if that disc be of felt),

or fitted into either or both of two arcuate grooves, according as one or both is present. One of such grooves is indicated at 11c in Fig. 2, this on the upper side of disc 11; and the other being indicated at 12e in Fig. 3, 70 this on the underside of disc 12.

75 Where the disc 11 is of felt or some similar soft and yielding material, the attaching flanges of the glove-fastener elements 14 will sink therein, as illustrated in Fig. 5; if, in finally coupling up the discs, to establish the complete device as shown in Fig. 1, the design of the glove-fasteners 14—15 is such as to urge the disc into face-to-face contact.

80

Operation

As aforesaid, said device is shown applied to the hair strand 8 of Fig. 1, and here the discs 11 and 12, following the passing of the root portion of the hair strand through the aligned slots 11b and 12b, are illustrated as having been relatively fractionally rotated to cause said discs to coact to become completely embrasive of the hair strand.

Now, said hair strand is wound relative to 90 the posts 10a; in any one of several ways, as will now be described, but always to present a compact column of hair of a size or shape convenient for use, when desired, with any standard form of heat applying sleeve, however heated, as used in present or future permanent waving machines. The device may of course be used for giving a wave to persist only until the next washing, as by applying a semi-permanent lotion to the hair, and then 100 leaving the hair wound on the device for a long enough period to become air-dried.

Some of the many possible coilings of the hair strand are illustrated very clearly in Fig. 4, when examined in the light of the 105 showing of Fig. 1. The hair strand, after issuing through the now closed hole formed by the openings 11a and 12a following the throwing of slots 11b and 12b out of registry as last above explained, is, generally (if a true long 110 natural wave, such as that illustrated at W in Fig. 6, is to be given to the lower subdivision of the strand) wound as shown in Fig. 1 and as indicated in dot and dash lines in Fig. 4. This winding of the strand involves, it 115 will be noted, a series of continuously reversing coils; that is, a first coil wound around one post in one direction, a second coil wound around the other post in the opposite direction, a third coil wound around the first post in the first direction, and so on. This reversely curved coiling up of the hair strand may continue all the way to the top of the post; or, if the strand be very long, to the top of the post and then down spirally over the 120 previously wound hair on the two posts, and finally suitably tied. Where, as is now thought to be ideal, a tendril effect is desired at a terminal subdivision of the hair strand, following a wave effect between such tendrils 125

130

and the hair roots, the operation illustrated in dot and dash lines in Fig. 4 and just described is continued for as many convolutions as desired, say part way up the posts 10a, 5 and then the remaining part of the strand is wound spirally around the two posts, or around one thereof, before being finally tied; this latter waving operation being illustrated clearly in Fig. 4, in broken lines, thereby to 10 produce tendrils as shown at T in Fig. 6. And, if this part of the strand be very long, the spiralling of the strand around said post, after reaching the top thereof, can be continued downwardly along the hair already 15 thereon, as indicated in dotted lines in Fig. 4. As is usual, in any case, the last wound portion of or tip of the strand may be temporarily secured in place relative to the posts or to one of the posts. A common form of tying 20 string for the purpose as illustrated in Fig. 4 at 16, located at the tip of the strand which has finally been wound as indicated in dotted lines in this view.

Since the posts 10a may laterally give toward each other, very many different effects 25 are possible, according as the strand of hair is wound wholly or partially about one or both posts. Also, and this is a very important point, the hair filaments cannot be broken 30 or damaged in any way, due not only to the resiliency of such posts, permitting a yield toward each other, but because in the case of the reversely looped strand portions there is considerable elasticity and give.

35 Considerable particularities of description, as to materials, part details, dimensions, capacities and utilities may have been herein indulged in, but it will be understood that these statements, made with particular reference to that one, and the one now preferred, of the many possible embodiments of the invention which is illustrated in the drawings, are not in any way to be taken as definitive or limitative of the invention. In 40asmuch as many changes could be made in the above constructions, and many apparently widely different embodiments of the invention could be made without departing from the scope thereof, it is intended that all 45 matter contained in the above description or shown in the accompanying drawings shall be interpreted as illustrative and not in a limiting sense.

It is also to be understood that the language 50 contained in the following claims is intended to cover all the generic and specific features of the invention herein described, and all statements of the scope of the invention which, as a matter of language, might 55 be said to fall therebetween.

In other words, the scope of protection contemplated is to be taken solely from the appended claims, interpreted as broadly as is consistent with the prior art.

60 65 I claim:

1. In a hair waving device, the combination of a plurality of substantially parallel resilient posts, and a mounting therefor adapted to embrace a strand of hair between the scalp and the portion of the strand to be 70 waved.

2. In a hair waving device, stacked discs, each disc having a radial slot, the discs being movable relative to each other so that the slots may be moved into and out of registration with each other and positive fastening 75 means for releasably holding said discs together and adapted to allow relative movement of said disc while holding the same to each other.

3. In a hair waving device, stacked discs, each disc having a radial slot, the discs being movable relative to each other so that the slots may be moved into and out of registration with each other, positive fastening 80 means for releasably holding said discs together, one of said discs being slidable relative to said fastening means.

4. In a hair waving device, stacked discs, each disc having a radial slot, the discs being 85 movable relative to each other so that the slots may be moved into and out of registration with each other, positive fastening means for releasably holding said discs together, one of said discs being slidable relative to said fastening means, said fastening 90 means consisting of snap fasteners.

In testimony whereof I hereby affix my signature.
